UNITED STATES PATENT OFFICE.

EDWIN NORTON, OF PAGET WEST, BERMUDA.

SHEET-METAL BOX.

1,079,903.

Specification of Letters Patent.

Patented Nov. 25, 1913.

Application filed June 4, 1912. Serial No. 701,492.

To all whom it may concern:

Be it known that I, EDWIN NORTON, a citizen of the United States, residing at Paget West, Bermuda, have invented certain new and useful Improvements in Sheet-Metal Boxes, of which the following is a description, reference being had to the accompanying drawing and to the figures of reference marked thereon.

10 The invention relates to new and useful improvements in sheet metal boxes, and more especially to boxes which are stamped up in a single piece from sheet metal and are so constructed that one box may be nested within another, during shipment.

An object of the invention is to provide a box of the above character, with a supporting flange at its upper edge, on which the nested boxes rest so as to prevent the sides 20 of the boxes from wedging together.

A further object of the invention is to provide a box of the above construction with a coating of sealing material, which is placed inside of the curled flange on the body of the 25 can, whereby the curled portion of the flange protects the coating, and properly houses the same.

These and other objects will in part be obvious, and will in part be hereinafter more 30 fully described.

In the drawings which show by way of illustration one embodiment of the invention, Figure 1 is a sectional view through a plurality of boxes, which are nested together, 35 each of which embodies my invention. Fig. 2 is an enlarged detail showing the flange on the body of the box with the coating applied thereto, and before said flange is curled to protect the coat. Fig. 3 is a similar view 40 showing the flange after it is curled, and also the cover applied to the box. Fig. 4 is a similar view showing the flange on the cover, and the flange on the body of the box, rolled into a double seam. Fig. 5 is a plan view of 45 a box having my improvement applied thereto.

In carrying out the invention, I preferably form the body of the box from a single piece, by stamping the same from tin plate 50 or other sheet metal which may be coated with a non-corrosive substance. From certain aspects of the invention however, the sheet metal may be the ordinary black sheet having the inner surface thereof coated with 55 lacquer, aluminum, or any other non-corrosive material.

The invention relates more particularly to the construction of the box, and not to the material from which the box is made. Said box is formed with the sides thereof tapering 60 slightly outwardly toward their upper edges, whereby one box may be nested within the other. The upper edge of the box is formed with a flange which may be trimmed to the proper width. The under face of the flange 65 is coated with a suitable plastic sealing material, after which the outer edge of the flange is curled downwardly and inwardly, so as to provide a part projecting underneath the packing to protect the same, and this projecting part of the flange also serves as a support for the cans when nested together.

Referring more in detail to the drawings, the invention consists of a metal box 1, which is as above noted, stamped from a single 75 sheet of metal. The sides 2, of the box are tapered outwardly toward the upper edges 3 thereof. The bottom of the box is formed with a downwardly projecting bead 4. This bead 4 is located within the margin of the 80 bottom of the box, and between said bead and the margin of the box, said bottom is scored. The purpose of this bead and the scoring formed in the bottom, is to provide an easy way of opening the box. When the 85 box is closed, if pressure is applied to the bead 4 either by striking or otherwise, said bottom will be sheared off at the score 5, thus giving access to the contents of the box. This construction of the bottom of the box 90 forms no part of the present invention, but is shown, described and claimed, in my pending application, Serial No. 304,508, filed March 6th, 1906.

The upper edges 3 of the box 1 are bent 95 outwardly to form a flange 6. This flange may be trimmed so as to form a uniform flange of the desired width. The under face of the flange is coated with a coating roll or other means, so as to provide a strip of sealing material 7, which extends entirely around the flange on the box. After the coating is applied to the under face of the flange, said flange is curled as at 8 downwardly and inwardly, to provide an inwardly projecting lip 9, which projects over the coating applied to the flange.

When the boxes are nested as shown in Fig. 1, this lip 9 on the curled part of the flange, will rest on the upper face of the 110 flange of the box in which it is placed, and said inner box will thereby be supported by

the flange solely of the next adjacent outer box. In other words, this downwardly turned part of the flange is so proportioned that the inwardly bent part is spaced from 5 the outwardly bent part of the flange, and this inwardly bent part supports the boxes when they are nested, and thereby prevents the side faces of the boxes from wedging together, so as to permit the same to be 10 easily separated. By this construction, I am able to nest together for shipment, a number of boxes and thus reduce to a minimum the cost of shipment. Furthermore, when said boxes are nested, the packing or 15 the sealing material, will be effectively housed between the flanges of the boxes, and kept free from dust and dirt, and also from abrasion during transportation.

The cover 10 is shaped so as to fit within 20 the upper end of the box, and is formed with a flange 11 adapted to rest upon the flange formed in the body of the box, and also to be rolled into a double seam with said flange on the box body. In Fig. 3 I have 25 shown the cover in place on the body of the box, with the flange projecting laterally therefrom. In Fig. 4, I have shown the two flanges rolled into a double seam and the packing or sealing material as effectively 30 closing or sealing said double seam. This roll or curl on the outer edge of the flange of the body of the box not only serves as a means for protecting the sealing material and as a means for supporting the boxes 35 when nested, but will also aid in the forming

of the double seam as the flange is thereby given an initial curl, which not only assists in rolling the same into a double seam, but also assists in the proper rolling of the flange on the cover into said double seam. 40

It is obvious that minor changes in the details of construction and in the shape of the box may be made, without departing from the spirit of the invention as set forth in the appended claim. 45

Having thus described my invention, what I claim as new and desire to secure by Letters Patent, is:—

A sheet metal box consisting of a bottom and side walls, said side walls being slightly 50 tapered outwardly toward their upper edges, whereby one box may nest in another, said side walls at their upper edges being bent outwardly to form a flange, said flange having a coating of sealing material applied 55 thereto on its under face, the outer edges of said flange being bent downwardly and inwardly, said inwardly bent portion of the flange being spaced from the outwardly bent portion thereof, whereby said sealing material is protected, and a support is formed 60 for the nested boxes which prevents said nested boxes from wedging together.

In testimony whereof, I affix my signature, in the presence of two witnesses.

EDWIN NORTON.
